HEAT EXCHANGER

Joseph A. Fabregas, Cassadaga, and Max E. Underwood, Dunkirk, N. Y., assignors to Alco Products, Inc., New York, N. Y., a corporation of New York

Application August 3, 1953, Serial No. 372,119

6 Claims. (Cl. 257—32)

This invention relates to heat exchangers and particularly to exchangers of the shell and tube type which are provided with sub-coolers.

The trend in high pressure heat exchangers, as exemplified by a feed water heater, is to employ a sub-cooling section to extract heat from the steam condensate thus increasing the total heat recovery from the steam. Steam supplied to sub-cooled exchangers must be isolated from the sub-cooler or the cooler's efficiency is impaired. For that purpose a valve or baffle is usually arranged between the condensing section and the sub-cooler so that a water seal is provided between the two to keep the steam out of the sub-cooler.

Any such water seal should leave exposed to the steam as much of the tubes as possible so that the maximum tube surface may be utilized for heat exchange. Moreover, the sub-cooler should be maintained substantially full of condensate. Meeting these requirements within the confines of a normally sized heat exchanger without resort to valves or mechanical controls to drain off the condensate from the condensing section and still provide for fluid movement in the most efficient heat exchange manner has heretofore been considered impossible.

The principal object of the present invention is to provide a heat exchanger of the described type in which a continuous drain of condensate from the condensing section to the sub-cooler is effected through a clear unrestricted passage without resort to the use of valves or other mechanical controls.

Another object of the invention is to provide a vertical heat exchanger of the channel-down type in which the condensate is kept at a low level in the condensing section and at a high level in the sub-cooler with means to effect a continuous drain of the condensate from the former to the latter without resort to valves or other mechanical controls.

Still another object is to provide a heat exchanger construction in which a continuous draining movement of condensate from the condensing section to the sub-cooler is produced by utilizing a pressure differential between the sub-cooler and condensing section to create a siphon between the condensing section and the sub-cooler while at the same time a water seal is maintained at the intake end of the siphon to keep steam out of the sub-cooler.

A further object is to provide such a construction which avoids expansion difficulties by having it mounted upon the floating tube bundle.

Other and further objects of the present invention will be apparent from the following description, the accompanying drawing, and the appended claims.

In the drawing, a vertical shell and tube type heat exchanger of the feed water heater class is shown schematically with the sub-cooler of the invention arranged therein.

The heat exchanger illustrated is a feed water heater of the shell and tube type and comprises a vertical shell 10, a bundle of U-tubes 11 (only one of which is shown

2

although the tubes need not be U-shaped), and a channel or water box 12 whose upper wall 13 acts as a tube sheet. Channel 12 is divided by wall 14 into two compartments 15 and 16. Feed water to be heated is supplied through inlet nozzle 17 to compartment 15 whence it passes upward into the tubes. Steam supplied through inlet nozzle 18 encounters the tubes and gives up heat to the water. The steam is condensed and drawn off through outlet nozzle 19 in the manner later described. 5 The heated water passes down into compartment 16 whence it is drawn off through outlet nozzle 21 to a point of use. A plate 22 may be arranged opposite steam inlet nozzle 18 to prevent a direct blast of steam against the tubes.

10 The shell contains upper and lower condensing sections 23 and 24 and a condensate sub-cooler generally indicated at 25. The shell is foreshortened in the drawing as the upper condensing section 23 is of considerable height. The sub-cooler 25 comprises an open top condensate reservoir 26 formed by a wall 27 which encloses the lower portion of the intake ends of the U-tubes. Wall 27 is supported by channel wall 13 and is spaced from the shell by integral radial flange 28 which is preferably secured to the latter although wall 27 may be entirely secured to wall 13 and still have suitable condensate outlet means. The upper end of reservoir 26 is open for the reception of condensate and its lower end is in communication with draw-off nozzle 19. A series of baffles 29 extend inwardly into the reservoir from the wall 27 to 15 provide a restricted flow zone to maintain a path of maximum distance for the condensate flowing down through the sub-cooler to draw-off nozzle 19.

20 Steam condensed in that part of the upper condensing section 23 which is vertically above the sub-cooler drops directly into the reservoir. Steam condensed in the remainder of the upper condensing section 23 is collected by dam or plate 31 and pours into the sub-cooler reservoir 26. Plate 31, which is arranged above and to one side of the sub-cooler preferably overlaps the open end 25 and is formed with holes shaped and arranged so that it may be mounted on the tube bundle in fluid tight relation thereto. A rim portion 32 is formed on the plate and extends almost completely around its periphery. The rim is interrupted at the side of the plate adjacent the sub-cooler so that an opening is provided to permit the flow of condensate from the plate into the sub-cooler. Thus most of the condensed liquid is funneled or directed into the open top of the sub-cooler. Steam which is not condensed in the upper condensing section 23 passes under plate 31 and reaches the lower condensing section 24 where it is condensed and collected in the bottom of the lower condensing section 24 to form a second reservoir or sealing pool above the channel wall 13.

25 Offset from sub-cooler wall 27 and connected thereto is a second wall 33 which extends downwardly to terminate a short distance above channel wall 13 in the preferred embodiment. An opening 34 is formed in sub-cooler wall 27 opposite the upper portion of offset wall 33. Wall 33 extends a substantial distance along wall 27 and is joined thereto at its ends so that a passage 35 is provided to establish communication between opening 34 and the condensate reservoir formed in the lower portion of the lower condensing section. Condensate collected in such lower section passes through passage 35 30 into the sub-cooler reservoir by a siphon action.

35 Within the sub-cooler, the fluid pressure at the top of the reservoir is greater than at the outlet nozzle 19. The reason for the pressure differential is that the condensate, in following its circuitous path down the baffled length 70 of the sub-cooler to nozzle 19, is subjected to friction and orifice losses. These losses are, however, absent in lower condensing section 24 so that the pressure at the

bottom of this section is higher than at the corresponding level within the sub-cooler section. Conditions for a siphon action are therefore present in which condensate flows from the condensing section 24 upwardly through passage 35 into the sub-cooler. Additional heat may thus be extracted from the siphoned condensate in the sub-cooler.

As previously stated in the objects of the invention, it is desirable to keep as much as possible of the tubes in the condensing sections 23 and 24 exposed to the steam in order that their full condensing capacity may be utilized. The tubes cannot be exposed below the end of offset wall 33, however, because steam would then pass into the sub-cooler and impair its efficiency. Consequently, a level of condensate sufficient to safely cover the intake opening of passage 35 at maximum operating conditions is required. This then locates the position or height of opening 34, i. e. it is determined for maximum operation of the heat exchanger by considering certain variables as set out below. At less than maximum operating conditions, the level of the condensate in lower condensing section 24 rises to adjust itself to the fluid head required for continuous operation of the siphon effect. It is also desirable that the sub-cooler reservoir be kept nearly full so that the temperature of the water entering at nozzle 17 will be as close as possible to the temperature of the condensate passing out through nozzle 19. Maximum extraction of heat is thus insured.

The location of opening 34 and the level of the water maintained in the reservoir at the bottom of condensing section 24 depends on the conditions of pressure balance as determined for each particular construction. Factors to be considered in this connection are the design of reservoir wall, baffle size and arrangement, static head, and expected load conditions.

In operation, open ended sub-cooler reservoir 26 is maintained substantially full of hot condensate by dam 31 to warm the incoming water which is further heated as it passes through the U-tubes to compartment 16 and outlet nozzle 21. By automatic adjustment of liquid heads, a water seal is maintained by the pool of condensate in condensing section 24 which covers the intake opening of passage 35 to keep steam out of the sub-cooler. By means of the siphon action described, the level of the condensate in lower condensing section 24 is maintained at a point determined by load conditions and the excess condensate is carried into the sub-cooler reservoir where heat is extracted from it. It thus is apparent that maximum tube area in condensing section 24 is exposed to the steam during the second or high temperature pass of the fluid to be heated.

When the unit is in operation at maximum capacity, the flow of condensate through the sub-cooler is at a maximum rate. Hence the condensate flow through passage 35 is likewise at maximum. The condensate in condensing section 24 is at its lowest level so that almost all the surface of the tubes is available for condensing surfaces. At less than maximum performance, the condensate flow through the sub-cooler diminishes which, in turn, diminishes the condensate flow through siphon passage 35. The condensate level in section 24, accordingly, rises to cover a portion of the tube surface. Since the performance is not at a maximum, the slight loss of effective surface is not of consequence. It thus appears that the invented construction automatically compensates for changes in load and performance without the use of separate controlling devices. By use of the open ended subcooler and dam to direct the condensate, the sealing means normally used to close the top of the subcooler is eliminated.

While there has been hereinbefore described an approved embodiment of this invention, it will be understood that many and various changes and modifications in form, arrangement of parts and details of construction thereof may be made without departing from the

spirit of the invention, and that all such changes and modifications as fall within the scope of the appended claims are contemplated as a part of this invention.

What we claim is:

- 5 1. A heat exchanger comprising a vertical shell having a steam inlet, a plurality of tubes extending vertically of said shell, a channel structure connected to said shell and associated with said tubes to provide for the passage of fluid therethrough, a vertical subcooler within the shell enclosing part of the tubes and being open at the upper end to communicate with the shell interior, a condensate outlet from said subcooler, and a passage connecting the lower end of the shell interior with a higher interior point of the subcooler.
- 10 2. A heat exchanger comprising a vertical shell having a steam inlet, a plurality of tubes extending vertically of said shell, a channel structure connected to said shell and associated with said tubes to provide for the passage of fluid therethrough, a vertical subcooler within the shell enclosing part of the tubes and being open at the upper end to communicate with the shell interior, a condensate outlet from said subcooler, means spaced above said open end to direct condensate into the subcooler, and a passage connecting the lower end of the shell interior with a higher interior point of the subcooler.
- 15 3. A heat exchanger comprising a vertical shell having a steam inlet, a plurality of tubes extending vertically of said shell, a channel structure connected to said shell and associated with said tubes to provide for the passage of fluid therethrough, a vertical subcooler within the shell enclosing part of the tubes and being open at the upper end to communicate with the shell interior, a condensate outlet from said subcooler, means carried by the tubes and spaced above said open end to direct condensate into the subcooler, and a passage connecting the lower end of the shell interior with a higher interior point of the subcooler.
- 20 4. A heat exchanger comprising a vertical shell having a steam inlet, a plurality of tubes extending vertically of said shell, a channel structure connected to said shell and associated with said tubes to provide for the passage of fluid therethrough, a vertical subcooler within the shell enclosing part of the tubes and being open at the upper end to communicate with the shell interior, a condensate outlet from said subcooler, means spaced above said open end to divide the shell interior into an upper and lower condensing section, said means collecting condensate from said upper section and directing it into the open end of said subcooler, a second condensate reservoir at the bottom of the shell adjacent the subcooler, and a passage extending from the second reservoir to the subcooler reservoir to siphon condensate from the second reservoir to the subcooler reservoir.
- 25 5. A heat exchanger comprising a vertical shell having a steam inlet, a plurality of tubes extending vertically of said shell, a channel structure connected to said shell and associated with said tubes and having means providing for the passage of fluid through said tubes in a plurality of passes, a vertical subcooler occupying a portion of the shell cross sectional area and supported by said channel and enclosing all of the tubes in the first pass for a portion of their length, said subcooler being open at its top to the interior of the shell, means spaced above said open end and substantially occupying the rest of said shell cross sectional area to direct condensate into the subcooler, and a passage connecting the lower end of the shell interior with a higher interior point of the subcooler.
- 30 6. A heat exchanger of the vertical channel-down type comprising a shell having a steam inlet, a plurality of tubes extending vertically of said shell, means for directing fluid in a plurality of passes through the tubes, a vertical subcooler supported by the channel enclosing all of the tubes in the first pass for a portion of their length and occupying a part of the lower portion of the shell,
- 35 7. A heat exchanger comprising a vertical shell having a steam inlet, a plurality of tubes extending vertically of said shell, a channel structure connected to said shell and associated with said tubes to provide for the passage of fluid therethrough, a vertical subcooler within the shell enclosing part of the tubes and being open at the upper end to communicate with the shell interior, a condensate outlet from said subcooler, means spaced above said open end to direct condensate into the subcooler, and a passage connecting the lower end of the shell interior with a higher interior point of the subcooler.
- 40 8. A heat exchanger comprising a vertical shell having a steam inlet, a plurality of tubes extending vertically of said shell, a channel structure connected to said shell and associated with said tubes to provide for the passage of fluid therethrough, a vertical subcooler within the shell enclosing a portion of the inlet ends of the tubes, said subcooler being open at its upper end to the shell interior, means spaced above said open end to divide the shell interior into an upper and lower condensing section, said means collecting condensate from said upper section and directing it into the open end of said subcooler, a second condensate reservoir at the bottom of the shell adjacent the subcooler, and a passage extending from the second reservoir to the subcooler reservoir to siphon condensate from the second reservoir to the subcooler reservoir.
- 45 9. A heat exchanger comprising a vertical shell having a steam inlet, a plurality of tubes extending vertically of said shell, a channel structure connected to said shell and associated with said tubes and having means providing for the passage of fluid through said tubes in a plurality of passes, a vertical subcooler occupying a portion of the shell cross sectional area and supported by said channel and enclosing all of the tubes in the first pass for a portion of their length, said subcooler being open at its top to the interior of the shell, means spaced above said open end and substantially occupying the rest of said shell cross sectional area to direct condensate into the subcooler, and a passage connecting the lower end of the shell interior with a higher interior point of the subcooler.
- 50 10. A heat exchanger of the vertical channel-down type comprising a shell having a steam inlet, a plurality of tubes extending vertically of said shell, means for directing fluid in a plurality of passes through the tubes, a vertical subcooler supported by the channel enclosing all of the tubes in the first pass for a portion of their length and occupying a part of the lower portion of the shell,
- 55 11. A heat exchanger comprising a vertical shell having a steam inlet, a plurality of tubes extending vertically of said shell, a channel structure connected to said shell and associated with said tubes to provide for the passage of fluid therethrough, a vertical subcooler within the shell enclosing part of the tubes and being open at the upper end to communicate with the shell interior, a condensate outlet from said subcooler, means spaced above said open end to direct condensate into the subcooler, and a passage connecting the lower end of the shell interior with a higher interior point of the subcooler.
- 60 12. A heat exchanger comprising a vertical shell having a steam inlet, a plurality of tubes extending vertically of said shell, a channel structure connected to said shell and associated with said tubes and having means providing for the passage of fluid through said tubes in a plurality of passes, a vertical subcooler occupying a portion of the shell cross sectional area and supported by said channel and enclosing all of the tubes in the first pass for a portion of their length, said subcooler being open at its top to the interior of the shell, means spaced above said open end and substantially occupying the rest of said shell cross sectional area to direct condensate into the subcooler, and a passage connecting the lower end of the shell interior with a higher interior point of the subcooler.
- 65 13. A heat exchanger comprising a vertical shell having a steam inlet, a plurality of tubes extending vertically of said shell, a channel structure connected to said shell and associated with said tubes and having means providing for the passage of fluid through said tubes in a plurality of passes, a vertical subcooler occupying a portion of the shell cross sectional area and supported by said channel and enclosing all of the tubes in the first pass for a portion of their length, said subcooler being open at its top to the interior of the shell, means spaced above said open end and substantially occupying the rest of said shell cross sectional area to direct condensate into the subcooler, and a passage connecting the lower end of the shell interior with a higher interior point of the subcooler.
- 70 14. A heat exchanger of the vertical channel-down type comprising a shell having a steam inlet, a plurality of tubes extending vertically of said shell, means for directing fluid in a plurality of passes through the tubes, a vertical subcooler supported by the channel enclosing all of the tubes in the first pass for a portion of their length and occupying a part of the lower portion of the shell,
- 75 15. A heat exchanger comprising a vertical shell having a steam inlet, a plurality of tubes extending vertically of said shell, a channel structure connected to said shell and associated with said tubes to provide for the passage of fluid therethrough, a vertical subcooler within the shell enclosing part of the tubes and being open at the upper end to communicate with the shell interior, a condensate outlet from said subcooler, means spaced above said open end to direct condensate into the subcooler, and a passage connecting the lower end of the shell interior with a higher interior point of the subcooler.

said subcooler being open at its top to the interior of the shell, a series of circuitous flow baffles in the subcooler, a condensate collecting plate carried by the tubes and spaced above the subcooler over the unoccupied lower portion of the shell, and an enclosed passage connecting the lower unoccupied portion of the shell interior with the interior of the subcooler at a predetermined height from the lower end thereof.
